UNITED STATES PATENT OFFICE.

JOHN S. CAMPBELL, OF SLATER, MISSOURI.

FOLDING EGG-CRATE.

SPECIFICATION forming part of Letters Patent No. 793,819, dated July 4, 1905.

Application filed January 18, 1904. Serial No. 189,544.

To all whom it may concern:

Be it known that I, JOHN S. CAMPBELL, a citizen of the United States, residing at Slater, in the county of Saline, State of Missouri, have 5 invented certain new and useful Improvements in Folding Egg-Crates; and I do hereby declare the following to be a full, clear, and exact description of the invention, such as will enable others skilled in the art to which it appertains to make and use the same.

This invention relates to collapsible crates; and it has for its object to provide a crate which when not in use may be folded to occupy a small space, which may be easily and 15 quickly unfolded or set up, and which will be held firmly in its unfolded position.

A further object of the invention is to provide a crate wherein the several members will be securely braced and a durable structure 20 will be provided.

In the drawings forming a portion of this specification, and in which like numerals of reference indicate similar parts in the several views, Figure 1 is a perspective view showing the crate set up and with its cover removed. Fig. 2 is a vertical section taken longitudinally through the crate with the cover in place. Fig. 3 is a transverse section taken 25 vertically through the crate with the cover in place. Fig. 4 is a vertical section taken longitudinally through the crate with the parts in their folded position.

Referring now to the drawings, there is shown a crate comprising a bottom 5, at the 30 end edges of which are hinged the ends 6 and 7 of the crate, one leaf, 8, of each hinge being secured against the upper face of the bottom of the crate, while the other leaf, 9, is secured against the inner face of the end of the crate 35 and extends above the upper edge of the latter and has a perforation 9' at a point above said upper edge.

Each side of the crate comprises two members, including the lower members 10 and 11, 40 which are fixed rigidly to the bottom 5, the member 10 being of a height substantially equal to the thickness of each end of the crate, while the member 11 is of a height equal to the thickness of an end plus the thickness of

the upper member 12 of the opposite side. 50 Above the lower member 11 is an upper member 13. The upper members 12 and 13 are connected to the lower members 10 and 11 by means of hinges, there being illustrated two 55 hinges for each side of the crate, the hinges of one side being diametrically opposite to those of the other side, so that the hinges are in transverse pairs. Each transverse pair of hinges includes a bar or metal strap 14, disposed transversely of the upper face of the 60 bottom 5 of the crate and having its ends turn upwardly against the inner faces of the members 10 and 11, at the upper edges of which they terminate and are connected to the leaves 15 and 16, which are secured against the inner 65 faces of the upper members 12 and 13 of the sides. The upper ends of the leaves 15 and 16 project slightly above the upper edges of the members 12 and 13 of the sides of the 70 crate and are adapted to enter openings 18 at the ends of the heads 19 of T-shaped braces, the stems 20 of which have openings 21, in which are received the upper ends of the leaves 9 of the end hinges. When these T-shaped braces or ties are engaged with the 75 ends of the hinge-leaves, they hold the sides and ends of the crate with their end edges in close contact.

The T-shaped braces are secured to the under side of a lid 22, which is adapted to fit 80 upon the crate and has openings therein which align, respectively, with the openings 18 and 21, above referred to, and receive in connection therewith the upper ends of the leaves 9, 15, and 16. The perforations 9' lie above the 85 upper face of the cover or lid, and through them are engaged pins 23, which serve to hold the cover or lid with the T-shaped braces against upward displacement.

When the crate is to be folded, the pins are 90 withdrawn and the cover, with the T-shaped braces, is removed. The ends of the crate are then folded inwardly upon the bottom 5, the upper member 12 of one side is folded downwardly upon the ends, the lid or cover is disposed upon the member 12, and the member 13 is then folded downwardly upon the lid or cover, the parts being held in their folded po- 95

sitions by means of hooks 23', attached to the free edge portion of the member 13 and engaged with pins 24 at the edge of the bottom.

In practice modifications of the specific construction shown may be made and any suitable materials and proportions may be used for the various parts without departing from the spirit of the invention.

What is claimed is—

- 10 1. A folding crate comprising a bottom, ends, a hinge for each end comprising a leaf attached to the bottom and a leaf attached to the inner face of the end and projecting thereabove, sides each comprising a lower member fixed to the bottom, and an upper member adapted to aline with the lower member, hinges connecting the upper and lower members of each side and each comprising a leaf secured to the upper member and projecting thereabove, and a T-shaped brace at each end of the crate, through the stem of which the projecting portion of the leaf at the corresponding end of the crate is engaged and through the ends of the head of which the projecting portions of the side leaves at the corresponding end of the crate are engaged.
- 15 2. A crate comprising a bottom, ends, a hinge for each end comprising a leaf attached to the bottom and a leaf attached to the inner

face of the end and projecting thereabove and 30 having a perforation in its upper end portion, sides each comprising a lower member fixed to the bottom and an upper member adapted to aline with the lower member, hinges for the sides, the mutually opposite hinges of the sides 35 comprising a common leaf extending transversely of the bottom and upwardly of the lower members of the sides, said hinges comprising also leaves extending upwardly of the inner faces of the upper members of the sides 40 and projecting thereabove, a T-shaped brace at each end of the crate, through the stem of which the projecting portion of the leaf at the corresponding end of the crate is engaged and through the ends of the head of which the projecting portions of the side leaves at the corresponding end of the case are engaged, a lid having openings in which the upwardly-projecting ends of the hinge-leaves are received and above which the perforated hinge-leaves project, and locking-pins engaged in said perforations.

In testimony whereof I affix my signature in presence of two witnesses.

JOHN S. CAMPBELL.
